United States Patent Office.

ANDREW SMITH, OF DAYTON, OREGON.

Letters Patent No. 91,681, dated June 22, 1869.

IMPROVEMENT IN ELLIPSOGRAPHS.

The Schedule referred to in these Letters Patent and making part of the same.

To all whom it may concern:

Be it known that I, ANDREW SMITH, of Dayton, in the county of Yam Hill, and State of Oregon, have invented a new and improved Ellipsograph; and I do hereby declare that the following is a full, clear, and exact description of the construction and operation of the same, reference being had to the accompanying drawings, making a part of this specification; in which—

Figure 1 is a side view;

Figure 2, a bottom view; and

Figure 3 a section through line x x of fig. 1.

The object of this invention is to provide for public use a simple, cheap, and effective instrument for drawing ellipses, and so constructed that it can be easily adjusted to produce figures of any practicable size and shape.

In the drawings—

A is a bifurcated standard, arranged with its forked end downward, and terminating in sharp brads a a' , which hold the instrument firmly upon the drawing-card or paper. At its upper end the standard A terminates in a hinge, a , which connects it to a horizontal arm, B, one end of which it supports, as shown in fig. 1.

C is an upright metallic staff, terminating at its lower end in a needle, c , which sticks into the drawing-card or paper, as shown in fig. 1, and, with the two needles a a' , holds the instrument in position.

A short distance above the needle, and capable of being adjusted up or down on the staff, so as to enlarge or diminish the figures without changing their shape, is a pattern, D, of elliptical shape, and attached to the shaft in any desired manner. At its upper end, the staff extends through the end of the arm B, as seen in fig. 1, and may be clamped in any position by means of a set-screw, b.

This staff, thus constructed and attached to the arm B, serves to support a vertically-sliding and horizontally-revolving block, E, which is pressed downward by a spring, s, at its upper end. This block is provided with lugs e , to which is jointed an arm, F.

The arm F, at its lower end, is attached to and supports a nearly horizontal piece, G, that serves, among other uses, as a handle by which to rotate the arm F, and its supporting-block E, about the vertical staff or spindle C.

The inner end of the part G presses against the periphery of the pattern D, against which it is held by the action of a spring, t. It may, if thought necessary, be provided with a friction-roller, r, which shall travel around the edge of the pattern in the manner that will be readily understood from the drawing. A curved guide and brace, H, attached to the block E, and extending through a slot in the arm F, may be employed to prevent the joint at e from injury by torsion.

In a groove in the under side of the piece G is fit-

ted a metallic slide, I, which can be adjusted in or out, with reference to the spindle C, by means of a thumb-screw, J.

The pencil K is supported by the inner end of the slide I, and moves in or out with it. Any practicable method of attaching the pencil to the slide may be employed, but that which I employ is as follows:

A screw-stem, L, is fastened to the slide I, projecting downward from it. A hollow sleeve, or tube, M, screws upon this stem, and a tube, N, which holds the pencil, slips over or into the tube M. The whole arrangement is clearly shown by figs. 1 and 3.

The under side of the part G may be graduated, as shown in fig. 2, so that the effect which any movement of the slide I will have upon the figure to be drawn, may be accurately calculated beforehand.

The whole instrument is exceedingly simple, and perfectly adjustable in all its parts.

I am aware that an instrument somewhat resembling a combination of staff C, pattern D, arm F, and pencil K, has been heretofore employed for this purpose, and I do not claim such an arrangement, irrespective of the other parts herein described and shown.

The advantages of my improved instrument over the one referred to are, among others, the following, viz:

First, the two legs a a' , in connection with the needle c , support the instrument more firmly and steadily.

Secondly, the joint a enables it to be folded very compactly when not in use.

Thirdly, by placing the spring s above the block, instead of inserting it above the pencil, in the tube N, as in the instrument referred to, the action of the spring is not so much interfered with by the friction or cramping of the pencil in the tube, as the arm F is rotated around the spindle.

Fourthly, the guide H supports the arm F more perfectly.

Fifthly, the pencil is more easily and perfectly adjustable, by means of the slide I and screw J.

Sixthly, the part G serves as a more convenient handle for moving the pencil.

Seventhly, the friction-roller causes the parts to work more easily.

Having thus described my invention,

What I claim as new, and desire to secure by Letters Patent is—

In connection with the standards A A and arm B, I claim the combination and arrangement of the staff C, block E, arm F, pattern D, guide H, springs t s , slide I, screw J, and pencil-holder, all constructed to operate substantially as and for the purposes specified.

ANDREW SMITH.
